CLAIM

The ornamental design for a vehicle visor organizer strap, as shown and described.

DESCRIPTION

FIG. 1 is a front view of a vehicle visor organizer strap showing my new design;

FIG. 2 is a back view of the vehicle visor organizer strap; FIG. 3 is an end view of the vehicle visor organizer strap; and,

FIG. 4 is a side view of the vehicle visor organizer strap. The broken lines on the strap in FIG. 1 are understood to represent stitching.
